UNITED STATES PATENT OFFICE

CLARENCE E. LOMAX, OF OAK PARK, ILLINOIS, ASSIGNEE TO RESERVE HOLDING COMPANY, OF KANSAS CITY, MISSOURI, A CORPORATION OF DELAWARE

CONNECTER SWITCH

Application filed September 21, 1927. Serial No. 220,953.

This invention relates in general to automatic switches for telephone systems, and the object of the invention is the provision of a new and improved connecter switch.

Heretofore it has been found in practice that the application of ringing current to the line conductors of the called line often causes the line relay associated with the lineswitch of the called line to operate before the cut-off relay of the lineswitch has had time to disconnect the line relay.

The main object of the present invention is the provision of an improved circuit arrangement in a connecter switch for delaying the application of ringing current to the line conductors of the called line until the cut-off relay of the called line has had time to operate and disconnect the line relay. This is accomplished by the addition of a ringing relay which energizes in order to connect ringing current to the called line after the switching relay has operated. Incidentally this permits a number of springs heretofore operated by the switching relay to be operated by the ringing relay.

Another feature of the present invention relates to the novel circuit arrangements in the connecter switch for connecting dial tone to the calling line after a connecter switch is seized by the lineswitch of a calling line. The dial tone is provided to inform the calling subscriber that he may proceed with the dialling operation to complete the desired connection.

Referring now to the drawings, there is shown by means of the usual circuit diagrams the new and improved connecter switch H, a rotary lineswitch LS, and an individual subscriber's substation A.

The connecter switch H is of the well known Strowger vertical and rotary type and has access to automatic subscribers' lines such as the lines of substation A. In the present case, the connecter H is accessible to calling subscribers such as subscriber A, by way of their individual lineswitches such as LS.

The lineswitch LS is of the well known 50 rotary type in which the wipers have no

normal position and which have access to connecter switches such as connecter H.

The substation A consists of a calling device and the usual instrumentalities to enable the subscriber to carry on conversation. The line of substation A terminates in the lineswitch LS and connecter bank contacts in connecters such as connecter H.

With this general description of the drawings in mind, the operation of the circuits may now be explained in detail. For this purpose, it will be assumed that an automatic subscriber desires to obtain connection with subscriber A. The customary subscriber's substation and individual lineswitch being well understood by those skilled in the art and forming no part of the present invention, it is therefore believed that it will suffice to say that in response to the removal of the receiver by the calling subscriber, his individual lineswitch seizes an idle trunk leading to an idle connecter switch such as indicated by the reference character H. Let us assume that the connecter H is the connecter seized by the calling lineswitch. When the calling lineswitch comes to rest upon the contacts associated with the conductors 20, 21, and 22 the switching relay of the lineswitch completes an energizing circuit for the line relay 4 of the connecter as follows: from ground by way of normally closed springs controlled by armature 38, lower winding of line relay 4, normally closed springs controlled by armature 32, conductor 21, over

the intervening lineswitch and subscriber's loop back to conductor 20, normally closed springs controlled by armature 31, and through the upper winding of line relay 4 to battery. Line relay 4 at armature 34 and its working contact completes an energizing circuit for energizing the change over series relay 6 and the release relay 5 in series. Slow-to-release relay 5, upon energizing over the above traced circuit, connects ground to the release conductor 22 at armature 36; said ground completing a holding circuit for maintaining the calling lineswitch in an operated position and, in addition, makes the trunk line to the con-

necter H busy to all other lineswitches having access thereto; at armature 37 and its working contact prepares the circuit for the vertical magnet 13, and at its resting contact 5 opens a point in the release circuit; and at armature 35 prepares a locking circuit for ring cut-off relay 7 and switching relay 11.

Slow-to-release change over relay 6, upon 10 energizing over the above traced circuit, closes a circuit at armature 39 for maintaining itself in operated position during the vertical impulses; at armature 40 disconnects the rotary series relay 10 and the 15 rotary magnet 14 at its resting contact and at its working contact prepares a circuit for operating vertical magnet 13. In addition, relay 6 at armature 38 disconnects ground from the lower winding of relay 4 and substitutes the normally grounded dial tone conductor 25 therefor. Responsive to 20 the connection of dial tone to the lower winding of line relay 4 an audible tone is transmitted to the calling subscriber over the circuit previously traced for the line 25 relay 4. When the calling subscriber hears the dial tone he will proceed to dial the called subscriber's telephone number.

The calling subscriber may now manipulate 30 the calling device in accordance with the digits in the telephone number of the desired called subscriber. Due to the operation of the calling device by the calling subscriber, the circuit of the line relay 4 is interrupted a plurality of times in the well known manner and the line relay responding 35 to these circuit interruptions, deenergizes a like number of times. Each time line relay 4 deenergizes a circuit is closed 40 for energizing the change-over relay 6 and vertical magnet 13 as follows: from ground by way of armature 34 in its resting contact, armature 37 and its working contact and armature 39 for maintaining slow-to- 45 release relay 6 in energized position and by way of armature 40 and its working contact to vertical magnet 13. By the operation 50 of the vertical magnet 13, the switch shaft and wipers are raised until the wipers 55 60, 61 and 62 are opposite the desired level of bank contacts in which the line conductors of the called line terminate. As soon as the switch steps off-normal, off-normal contacts 56 close thereby shorting the upper winding of the change-over relay 6. This 60 relay, being slow acting is maintained energized during the vertical impulses by way of its lower winding as previously described.

After the termination of the vertical 65 pulses, line relay 4 energizes and opens the circuit for maintaining the change-over relay 6 energized, whereupon said relay releases after an interval. Change-over relay 6, upon deenergizing, at armature 38 substitutes direct ground for conductor 25; and

at the resting contact of armature 40 prepares a circuit for the rotary magnet 14 and at its working contact opens the circuit of the vertical magnet.

The calling subscriber may now dial the 70 last digit of the called number. In response to the operation of the calling device by the calling subscriber, the circuit for the line relay 4 is again intermittently interrupted. Each time line relay 4 deenergizes a circuit is closed for operating the rotary magnet 14 and series rotary relay 10 as follows: ground by way of armature 34 and its resting contact, armature 37 and its working contact, armature 40 and its resting contact, resting contact of armature 45 and said armature, through the winding of rotary series relay 10 to battery, and by way of armature 55 and its resting contact thru the winding of rotary magnet 14 to battery. By the operation of the rotary magnet 14 75 the switch wipers are rotated step-by-step and are finally brought to rest in engagement with the particular set of contacts in which the line of substation A is terminated, these contacts being indicated in the drawings by reference characters 70, 71, and 72. The slow acting relay 10 is energized in multiple with the rotary magnet and maintains its armatures attracted throughout the rotary movement. At armature 50 series relay 10 opens the circuit of switching relay 11 and prepares a circuit including the busy relay 8 for testing the called line, and at armature 51 maintains its own circuit and the circuit 80 of the rotary magnet 14 independent of armature 45. The operation of the connector H now depends upon whether the called line is busy or not.

It will now be assumed that the line of 85 substation A is busy when called. Under these circumstances there will be a ground potential upon the contact 72 and when the test wiper 62 comes to rest in engagement therewith the busy relay 8 will be energized over a circuit as follows: ground on test contact 72, test wiper 62, armature 50 and its working contact, armature 47, and winding of busy relay 8 to battery. Shortly after the impulses cease, slow acting series 90 relay 10 deenergizes and completes a locking circuit for the busy relay as follows: ground by way of grounded release trunk conductor 22, armature 44 and its working contact, normally closed springs controlled by armature 50, armature 47, and winding of busy relay 8 to battery. Busy relay 8, upon energizing, at armature 45 opens the circuit of the rotary magnet 14, and at armature 46 connects the busy tone to conductor 115 21. The calling subscriber is now given the busy tone in the well known manner.

When the calling subscriber hears the well known busy tone, he will replace his receiver thereby opening the circuit of line 120 125 130

relay 4. At armature 34 and its working contact line relay 4 opens the circuit of slow-to-release relay 5 which thereupon de-energizes, and at armature 34 and its resting contact prepares a circuit for energizing the release magnet 12. Slow-to-release relay 5, upon deenergizing, at armature 36 removes ground from the release trunk conductor 22 thereby permitting the release of the calling lineswitch and by the removal 5 of ground from the release trunk conductor 22 the locking circuit of the busy relay 8 is opened whereupon said relay deenergizes. At armature 37 and its resting contact release relay 5 closes a circuit for energizing the release magnet 12 as follows: ground by way of armature 34 and its resting contact, armature 37 and its resting contact, armature 33, off-normal springs 57, 10 and the winding of the release magnet 12 to battery. The release magnet 12 energizes over the above traced circuit and restores the switch wipers to their normal position after which the off-normal springs 57 open 15 the circuit of the release magnet 12 in the usual manner. All the apparatus used to extend the connection are in normal position and may be used for other calls.

Having explained what occurs when the 20 called line is busy, it will now be assumed that the called line is idle. Such being the case, when the test wiper 62 comes to rest in engagement with a test contact 72, it will find no ground potential and the busy 25 relay 8 will not be energized. Instead, when the slow acting relay 10 falls back, a circuit is closed through the lower winding of the switching relay 11 as follows: from ground by way of armature 36, armature 44 and its resting contact, lower winding of switching relay 11, resting contact of armature 50 and said armature, wiper 62, bank contact 72, conductor 74, winding of cut-off relay 76, and winding of magnet 81 to battery. Upon the closure of the above 30 traced circuit the cut-off relay 76 of the lineswitch LS operates to clear the line of the substation A from its normal battery and ground connections in the lineswitch LS. Because of the well known mechanical interlocking arrangement of the rotary lineswitch the wipers of the lineswitch are not connected up at this time. In practice, 35 due to faulty adjustment of the cut-off relay, it may pull up a trifle slowly with the result that if ringing current is at once applied to the called line the line relay will flutter momentarily. In order to overcome 40 this, ringing relay 9 has been added in the connector which has its energizing circuit closed when the switching relay is fully operated. The interval of time that it takes 45 the switching relay and then the ringing relay to energize is sufficient to enable the 50 cut-off relay to be fully operated before the

ringing relay applies ringing current to the line.

The switching relay 11, upon energizing, 55 closes at armature 53 a locking circuit for itself through its upper winding; and at armature 52 connects ground to test contact 72 in order to make the called line busy to other switches having access thereto. At armature 55 switching relay 11 also opens the circuit of the rotary magnet 14; and at 60 armature 54 closes a circuit for energizing ringing relay 9. Armature 54 is adjusted to close its contacts near the end of its stroke so as to increase the time interval between the closure of the circuit for the cut-off relay and the closure of the circuit for the ringing relay. Ringing relay 9 at armature 65 65 opens a point in the circuit of the busy relay 8 and at armatures 48 and 49 connects ringing current to the line conductors of the connector H for ringing the called subscriber A. The ringing circuit may be traced as follows: interrupted generator Int. Gen., armature 48, lower winding of ring cut-off relay 7, resting contact of armature 41 and 70 said armature, wiper 60, bank contact 70, subscriber's line conductor 73, the bridged ringer and condenser at substation A, subscriber's line conductor 75, bank contact 71, wiper 61, armature 43 and its resting contact, armature 49 and its working contact, and resistance R to battery. Ring back tone is connected to the calling subscriber 75 by way of armature 58 in the usual manner.

When the called subscriber answers, the 80 ring cut-off relay 7 energizes and at armature 42 completes a locking circuit for itself by way of armature 35. At armatures 41 and 43 relay 7 disconnects ringing current from the called line and completes the talking circuit between the calling and called subscribers, and in addition, completes a circuit for energizing the back bridge relay 3 over the called subscriber's loop. Back bridge relay 3, upon energizing, reverses the 85 flow of current to the calling subscriber's line at armatures 31 and 32, at armature 30 connects ground to the conductor 59 for maintaining relays 7 and 11 operated, and at armature 33 opens the circuit to the release magnet so that the connector switch cannot release until the called subscriber hangs up. The reversal of current to the 90 calling line may be used for operating a meter if desired. The connection now having been completed, the calling and called subscribers may converse with each other as desired.

After the conversation and responsive to 95 the replacement of the receiver by the calling subscriber the circuit of line relay 4 is opened and said relay deenergizes. At armature 34 line relay 4 opens the circuit of slow-to-release relay 5 and in addition 100 prepares a circuit for operating the release 105

magnet 12. After the interval for which it is adjusted slow-to-release relay 5 deenergizes and at armature 36 removes ground from release conductor 22. After the line relay 4 deenergizes and before slow-to-release relay 5 deenergizes a circuit is closed for operating the rotary series relay 10 as follows: ground by way of armature 34 and its resting contact, armature 37 and its working contact, armature 40 and its resting contact, resting contact of armature 45 and said armature, and winding of relay 10 to battery. Relay 10, upon energizing, at armature 50 removes the ground extending by way of armature 52 and the lower winding of switching relay 11 from the release trunk conductor 22 so that when the release relay 5 subsequently deenergizes and removes ground from release trunk conductor 22 at armature 36, relay 10 clears the release trunk conductor 22 of all ground connections to permit the preceding switch or switches to release in the usual manner. Release relay 5, upon deenergizing, at armature 37 and its working contact opens the circuit of the series relay 10 and at armature 37 and its resting contact prepares a circuit for the release magnet 12 which circuit, however, is open at armature 33. After the interval for which it is adjusted relay 10 releases and at armature 50 completes the following circuit for maintaining the connector H busy until the called man hangs up; ground by way of armature 52, armature 50 and its resting contact, lower winding of switching relay 11, resting contact of armature 44 and said armature, to release trunk conductor 22.

When the called subscriber A replaces his receiver the circuit of the back bridge relay 3 is opened at the substation whereupon said relay releases. Relay 3, upon deenergizing, at armature 30 opens the locking circuits of the ring cut-off relay 7 and the switching relay 11 whereupon the latter relays release. The switching relay at armature 54 opens the circuit of the ringing relay 9, whereupon said relay releases. At armature 33 back bridge relay completes the circuit for the release magnet 12 which thereupon energizes and restores the switch to normal in the same manner as previously described. Responsive to the deenergization of switching relay 11 the circuit for the cut-off relay 76 of the lineswitch LS is opened at armature 52 whereupon said cut-off relay releases in the usual manner. All of the apparatus used in establishing the connection is now in normal position and may be used for extending other calls.

In case the called subscriber is the first to replace his receiver the back bridge relay 3 would deenergize and the switch would be held in operated position until the calling subscriber hung up whereupon the line and

release relays would deenergize and complete the circuit for restoring the connector to normal position.

Having described my invention, what I consider to be new and desire to have protected by Letters Patent will be pointed out in the appended claims.

What I claim is:

1. In a telephone system, a line, normal conductors permanently connected therewith, a connector switch for connecting with said line through said normal conductors, a line switch individual to said line for extending a connection therefrom, a line relay in said line switch normally connected to said normal conductors, a cut-off relay in said lineswitch adapted when energized to disconnect said line relay from said normal conductors, a switching relay in said connector, a ringing relay in said connector adapted when energized to connect ringing current to said normal conductors, means for closing an energizing circuit for said switching and cut-off relays in series, and contacts on said switching relay for closing an energizing circuit for said ringing relay. 75 80 85 90 95

2. In a connector switch for use in telephone systems, a ring-cut-off relay, a pair of line wipers permanently connected to contacts on said ring cut-off relay, a switching relay, a ringing relay, means for energizing said switching relay, and contacts on said switching relay for closing an energizing circuit for said ringing relay to cause said ringing relay to energize and apply ringing current to said line wipers. 100 105 110

3. In a telephone system, means including a two digit vertical and rotary connector switch for completing a connection from a calling to a called subscriber's line, means responsive to the initiation of a call by a calling subscriber for extending his line to said connector switch, a relay in said connector energized responsive to said extension, and contacts on said relay for controlling the connection and disconnection of dial tone to the calling subscriber's line. 115 120 125

4. In a telephone system, means including a two-digit vertical and rotary connector switch for completing a connection from a calling to a called subscriber's line, means responsive to the initiation of a call by a calling subscriber for extending his line to said connector switch, a vertical and rotary change-over relay in said connector switch energized responsive to said extension and deenergized responsive to the cessation of the calling of the first digit of the desired number, and contacts on said relay for connecting and disconnecting a distinctive tone to the calling subscriber's line. 130

5. In a telephone system, a two-digit connector switch having a directly controlled 135

vertical movement and a directly controlled rotary movement for completing a connection from a calling to a called subscriber's line, a change-over relay in said connector for controlling the change-over from the vertical to the rotary movement, means for energizing said relay when the connector is seized, separate means for maintaining said relay energized during the vertical movement after which said relay deenergizes, and means controlled by said relay for connecting and disconnecting dial tone to the calling line responsive to the energized and deenergized positions, respectively, of said relay.

6. In a telephone system, a two-digit connector switch having a directly controlled vertical movement and a directly controlled rotary movement for completing a connection from a calling to a called subscriber's line, a change-over relay in said connector for controlling the change-over from the vertical to the rotary movement, an energizing circuit for said relay closed responsive to the seizure of said switch, means for short-circuiting said relay responsive to the first vertical movement of said switch, separate means for maintaining said relay energized during the vertical movement after which it deenergizes, and contacts on said relay for connecting dial tone to the calling line only during the time said relay is energized.

7. In a telephone system, a two-digit connector switch having a directly controlled vertical movement and a directly controlled rotary movement for completing a connection, a change-over relay in said connector for controlling the change-over from the vertical to the rotary movement, means for energizing said relay; means for short circuiting said relay responsive to the first vertical movement of the connector, and separate means for maintaining said relay energized during the vertical movement after which it deenergizes.

8. In a telephone system, a two-digit vertical and rotary connector switch, a change-over relay in said switch, off-normal springs in said switch normally open while the switch is in normal position and closed while the switch is in off-normal position, an energizing circuit for said relay including a winding on said relay, means for closing said circuit responsive to the seizure of said switch to energize said relay over said winding, means responsive to the first vertical movement of said switch for operating said off normal springs to short circuit said winding, and a second winding on said relay for maintaining said relay energized until after the vertical movement.

9. In a telephone system, a two-digit vertical and rotary connector switch, a change-over relay in said switch, off-normal springs

in said switch normally open while the switch is in normal position and closed while the switch is in off-normal position, an energizing circuit for said relay including a winding on said relay, means for closing said circuit responsive to seizure of said switch to energize said relay over said winding, means responsive to the first vertical movement of said switch for operating said off-normal springs to short circuit said winding, and means controlled by said relay for maintaining itself in energized position until after the vertical movement.

10. In a telephone system, a two-digit vertical and rotary connector switch, a change-over relay in said switch, means for energizing said relay responsive to the seizure of said switch, means for rendering said first means ineffective after the first vertical movement of the switch, and separate means exclusive of said first means for maintaining said relay energized until after the vertical movement of the switch.

11. In a telephone system, a two-digit vertical and rotary connector switch, a change-over relay in said switch having two windings, means for initially energizing said relay over its first winding, means for rendering said first winding ineffective to energize said relay after the first vertical movement of the switch, and means for subsequently maintaining said relay energized over its second winding until after the vertical movement.

12. In a telephone system, means including a two-motion automatic switch for extending a connection from a calling line, means responsive to the initiation of a call by a calling subscriber for extending his line to said switch, and means in said switch operated responsive to said extension for transmitting a distinctive tone to indicate to the calling subscriber that he may proceed with the call and effective upon completion of the first movement of said switch to disconnect said tone before the second movement of said switch begins.

In witness whereof, I hereunto subscribe my name this 14th day of September, A. D., 1927.

CLARENCE E. LOMAX.
